UNITED STATES PATENT OFFICE.

HEINRICH BECK, OF SCHENECTADY, NEW YORK, ASSIGNOR TO GENERAL ELECTRIC COMPANY, A CORPORATION OF NEW YORK.

ELECTRIC-ARC LAMP.

1,209,540.

Specification of Letters Patent. Patented Dec. 19, 1916.

Application filed April 23, 1915. Serial No. 23,349.

To all whom it may concern:

Be it known that I, HEINRICH BECK, a subject of the Duke of Saxe-Meiningen, in the German Empire, residing at Schenectady, county of Schenectady, State of New York, have invented certain new and useful Improvements in Electric-Arc Lamps, of which the following is a specification.

My invention has reference to improvements in electric arc lamps, its object being to prevent the accumulative effect of the tendency of the electrodes, and especially of the anode, to side burning, by rectifying the side burning effect at its initial stage or at any time during its progress.

The invention is more particularly applicable to arc lamps with carbon or carbonaceous electrodes and its greatest utility is found in its application to arc lamps for searchlights.

In arc lamps of the kind indicated it has been found that the electrodes, and particularly the anode, is not being consumed evenly across its arcing end, but that the consumption is, generally, more vigorous on one side of the electrode, whereby its end becomes slanting and the arc, and especially the crater, which in such electrodes is the real source of light, is obscured in a direction opposite the slant, thus diminishing the output of light. The causes of this side burning are manifold, one of them being the magnetic blow exerted upon the arc by the conductors which carry the current to or from the electrodes. This blow effect is being more or less neutralized by a variety of devices which operate to produce a blow effect in a direction opposed to that produced by the ordinary conductors which carry the current to or from the electrodes. These devices tend to keep the arc in its theoretical position, which in case of electrodes that are in alinement with each other is coincident with the axes of the electrodes. The devices here spoken of are known in the art as blow magnets. These may be permanent magnets or electromagnets, or also current carrying conductors disposed about the arc in a proper manner. When the electrodes are in axial alinement and when the operating current is of moderate intensity, say up to 10, 12 or 15 amperes, blow magnet arrangements properly designed have proved to be successful in pre-

venting the side burning of the electrodes. 55 But when the electrodes are not quite in alinement or are decidedly inclined toward each other, as is the case in arc lamps used in searchlights, and particularly with the heavy currents used in searchlights, which 60 frequently rise to 100 amperes and sometimes reach as high a value as 200 amperes, blow magnets have not proved successful; and, in place of them or in addition to them, resort was had to the rotation of the 65 electrodes about their own axes, whereby it was expected that the tendency to side burning would be shifted all around the circumference of the electrodes. In this manner the side burning has actually been 70 somewhat diminished; but it remains still serious enough to impede the uniform distribution of light from the crater of the anode.

By my invention side burning of the electrodes, and especially of the anode, is checked and effaced as soon as the tendency thereto manifests itself, and this can be done from moment to moment all throughout the trim, so that the anode is kept burning 80 square from beginning to end, whereby the best possible distribution of light by means of a reflector or otherwise is secured.

In accordance with my invention, particularly as applied to searchlights, the electrodes are rotated, preferably by an electric motor, each about its axis, and are fed forward at approximately the rate at which they are consumed, in the usual manner. The anode is usually in a substantially horizontal position with its arcing end toward the reflector of the searchlight, and the cathode, facing the anode, is inclined toward the horizontal and usually with its rear end downwardly, and the axes of the two electrodes are in a substantially vertical plane. 90

Now, by reason of the inclination of one electrode toward the other, and by reason of the practical impossibility of making the electrodes absolutely straight, and by reason of the practical impossibility of rotating the electrodes strictly about their mathematical axes, and possibly also by reason of unequal density of the body of the electrode, side burning still takes place, and 100 my invention provides means for discovering the tendency to side burning as soon as its effect becomes at all perceptible. The 105

means consists of an optical arrangement whereby an image of the arcing ends of the electrodes and of the arc between them is thrown upon a screen arranged within a comfortable view of the attendant or operator. This image reveals the least tendency to side burning as soon as it appears. If the anode burns sidewise to the extent of two or three millimeters, this fact is at once shown by the image. In order to check the continued side burning and again make the electrode face square, I have found that it is only necessary to stop the rotation of the electrodes at the proper phase for a few seconds, hardly ever more than ten seconds, although sometimes three or four seconds' stoppage is sufficient. After this has been done the rotation of the electrodes is again resumed until another tendency to side burning is revealed by the image on the screen, when the rotation of the electrodes is again stopped for a few seconds; and this is repeated as often as the side burning tendency is shown. In this manner the crater in the anode is maintained very symmetrical, and extends from the outer edge of the electrode conically inwardly toward the center, and when the electrode is of the cored type, as is usually the case, the core can be seen exactly in the center of the crater, while the wide part of the crater merges with the electrode surface and forms with it a smooth, sharp, knife edge.

In the accompanying drawing I have illustrated my invention as applied to and practised in connection with a searchlight as follows:

Figure 1 is a side elevation of the electrodes of a searchlight lamp showing part of the mechanism for rotating the electrodes; Fig. 2 is a side elevation of the electrodes indicating the effect of the side burning and also the position to which the anode is brought to efface the side burning; Fig. 3 is a front end elevation of a searchlight equipped with my improvement with the shutters partly broken away and a portion of the casing in section; and Fig. 4 is a side elevation of a searchlight casing with a portion broken away and equipped with my improvement.

Like numerals of reference indicate like parts all throughout the drawing.

The electrodes 1—2 pass loosely each through a boss 3 and are additionally guided by the grooved rollers 4 and are rotated either by hand or by an electric motor 4', through the intermediary of the cog gearing 5. This, as well as the means for feeding the electrodes, is a common arrangement and need not be described in further detail. The anode 1 is intended to be substantially horizontal and the cathode 2 is inclined thereto at an angle of about

14°, with its rear end downwardly and with its arcing end at a distance of about 22 millimeters from the face of the anode. The inclination of the cathode and the distance of the same from the face of the anode are so chosen with reference to the diameter of the anode that with the arrangement of the electrodes indicated the arc extends from the cathode in an upward curve toward and to the anode, playing mainly upon the upper half of the face of the anode and just touching the upper edge of the same. The particular angle of inclination of the cathode and the distance from each other of the electrodes above indicated fulfills the conditions of my invention when the diameter of the anode is about 16 millimeters. When the diameter of the anode is different, then the inclination of the cathode and the distance between the faces of the electrodes will be changed so as to bring about the result aimed at by this arrangement, namely, the playing of the arc mainly upon the upper half of the end face of the anode and just touching the upper edge of the same. This arrangement of the electrodes is important for the successful operation of my invention. In Fig. 1 the arcing end of the anode is shown square, that is to say, about at right angles to the axis of the electrode and the crater of the anode is indicated in dotted lines as symmetrical with reference to the body of the electrode and with its outer flaring mouth merging with the cylindrical surface of the electrode and forming with it a sharp knife edge. This is the manner in which the anode burns when it is controlled in accordance with my invention.

It will be noticed that the anode is represented in the drawing with a bend and this bend is shown boldly and very much exaggerated to indicate that the electrodes are not generally perfectly straight, so that when the electrode is rotated one side of its free end describes a smaller circle than the other. The same thing would happen if the electrodes were perfectly straight but did not pass through the boss or holder 3 with its axis coincident with that of the holder, but formed an angle with it. This is really practically unavoidable; it always happens and so do bends in the electrode, more or less pronounced happen, and these general and unavoidable conditions are intended to be indicated by the bold bend of the portion of the anode which projects from the holder toward the side which maintains the arc. The dotted line 6—6 indicates the axis of the rear part of the anode which is supposed in this case to coincide exactly with the axis of the holder 3, and it will be seen that when the anode is rotated about this axis that part of the end face of the electrode which is on the convex side of the bend will describe

smaller circle than the part of the end face which is next to the concave side of the bend. In consequence of this the part of the end face of the anode which is next to the convex side of the bend will be exposed to the action of the arc a longer time during each period of revolution than the diametrically opposite side of the electrode face. The result of this is that the anode does not burn off square. This would be true even if the arc passed in a straight line between the electrodes; but, as a matter of fact, with the arrangement of the electrodes here shown and described the arc does not so pass, but curves upwardly as indicated; and this arrangement, while on the one hand it tends to intensify the side burning, as will be readily understood, it is, on the other hand an important factor in the process of rectifying the side burning, as will presently appear. The effect of the arrangement described is that the arc, eating into the face of the anode acts upon the same like a chisel to which the proper inclination is given upon the face of a metal rod rotated in a lathe; it drills, so to speak, a cavity into the face of the anode, the mouth of said cavity (called the 'crater') being equal to the diameter of the anode, so that the crater merges with the cylindrical surface of the anode, forming there with the same a sharp knife-edge. The consequence of this formation is to still further promote the tendency to side burning because only very little material has to be burned away at any part of the crater edge to make this edge slanting instead of square.

In accordance with my invention means are provided for detecting the side burning effect as soon as it is at all perceptible, as indicated in Figs. 3 and 4. A short tube 7 projects from the casing 8 of the searchlight and the outer end of the tube is closed by a disk of ground or opalized glass 9. A system of mirrors or lenses or both is disposed within the casing in such manner as to project the image of the ends of the electrodes and of the arc between them upon the glass disk. As here shown there are two mirrors 10 and 11 and a condensing lens 12 between them so arranged that the image projected on the screen 9 would be a reversed image, as indicated at 1', 2', in Fig. 4; but the optical arrangement may be different from that indicated and it is not necessary that the image be a reversed one. The operator or attendant standing at the side of the searchlight has the image of the electrodes clearly in view. He sees these electrodes rotating, he sees the play of the arc between them, and sees clearly the effect of side burning when such occurs, in the manner indicated in Fig.

4, on the face of the ground or opalized glass screen.

As soon as side burning is observed the operator, in accordance with my invention, stops the motor, if such is used, by which the electrodes are rotated, by a key or switch 13, and he so times the stoppage that the side burned portion 14 of the anode comes below the active region of the arc, while the projecting lip 15 of the electrode, which is just opposite the side burned portion, stands within the region of the upwardly curved arc, as indicated in Figs. 2 and 4. This can be easily done, since the electrodes are rotated at a slow rate, about thirteen times per minute. When this has been done, the lip 15 and the portion immediately below it, embracing only a small amount of anode material, burn away rapidly and in a few seconds the anode is again squared, after which the rotation of the electrodes is again started.

In the manner hereinbefore described the side burning of the anode can be checked instantly as soon as the least tendency thereto is observed, and the side burning which has occurred can be effaced in a few seconds, so that the anode can be maintained with its end face perfectly square, and the light from the crater can, therefore, issue on all sides throughout a whole trim.

What I claim as new and desire to secure by Letters Patent of the United States, is:—

1. The method of checking and effacing the side burning of the anode of an arc lamp, which consists in directing the arc from the cathode at such an acute angle upwardly against the upper portion of the face of the anode as to just touch its upper edge and rotating the anode about its axis, observing the effect of side burning at its initial stage, stopping the rotation of the anode with the side burned portion outside the region of the arc until the anode face is squared, and then continuing the rotation of the anode.

2. The method of checking and effacing the side burning of the anode of an arc lamp, which consists in so directing the arc from the cathode eccentrically against the face of the anode as to just touch the edge of the latter and rotating the anode about its axis, observing the effect of side burning at its initial stage, stopping the rotation of the anode with the side burned portion outside the region of the arc until the anode face is squared, and then continuing the rotation of the anode.

In witness whereof I have hereunto set my hand this 19th day of April, 1915.

HEINRICH BECK.
